UNITED STATES PATENT OFFICE.

ALBERT C. FISCHER, OF CHICAGO, ILLINOIS, ASSIGNOR TO SERVICISED LABORATORIES, INC., OF CHICAGO, ILLINOIS, A CORPORATION OF ILLINOIS.

INTERLOCKING SHINGLE.

Original application filed August 16, 1920, Serial No. 403,894. Divided and this application filed December 31, 1923. Serial No. 683,608.

This invention relates to shingles, or the like, for use in weatherproofing roofs or other surfaces of buildings, and particularly to shingles, or the like, made of felt or other flexible fabric.

The object of the invention is to provide a construction of shingle, or the like, which will permit inter-engagement or interlock of its corners or portions adjacent to its lower end, with other shingles with which it laps when in use, and thereby offer resistance to the distortion of the lower end of the shingle from intended flat position in the covering; and particularly to provide such an engagement as will serve as a means for spacing both one row from another and one shingle from another in a given row.

Since the invention deals with the lower free ends of shingles, it is naturally applicable to shingles existing as tabs or subdivisions projecting from a strip which connects their upper ends and determines the spacing between them, as well as to shingles existing as individual pieces.

This application constitutes a division of United States Letters Patent No. 1,479,035, issued January 1, 1924, to the same inventor.

The present invention proceeds upon the principle of providing, in intermediate portions of shingles, openings or recesses which receive corners or other portions of restricted dimensions in a lapping shingle, and which limit penetration thereof in a manner to arrest one shingle with relation to the other in a definite predetermined position. Thus, if a shingle be provided in its body portion with a slot having closed ends and of restricted length, and in a position to receive a corner of an overlying shingle or other portion thereof having diverging sides, such corner or projection can be moved inward through the slot until its sides enter the ends of the slot, when the overlying shingle will be arrested and its position definitely determined; and this determination of position will be in the direction of watershed or spacing between successive rows of shingles as well as in a direction transverse thereto, or the direction in which individual shingles are spaced in the row.

In the accompanying drawings, in which

the preferred embodiment of the invention is shown by way of illustration—

Figure 1 is a face view of a single shingle; and

Figure 2 is a similar view showing a plurality of shingles assembled to provide a weatherproofing surface.

1 represents a shingle which may be of any approved outline, but is here shown in ordinary rectangular form. Symmetrically located in the body of this shingle are slots 2 having closed ends and occupying angular positions which adapt them to assume a relation extending from edge to edge of portions of restricted dimension on a shingle to be overlapped with the slotted shingle, for instance, the corners 3 of such an overlapping shingle, the diverging edges 3^a of which become a gauge or measure to determine the extent of penetration of the slots 2 by such corners when the shingles are assembled upon the structure to be weatherproofed. The spacing of the slots 2 from the sides and weather ends of the shingles will determine the extent of exposure to weather of the underlying shingle, and also the extent of lateral overlap between the shingles, and therefore determine the spaces between rows of shingles as well as the spaces between shingles in the rows.

Inasmuch as the illustrated embodiment of the invention discloses rectangular shingles, the slots 2 naturally assume a diagonal position with reference to the longitudinal and transverse axes of the shingle, but if employed in connection with shingles having different shapes of projections, the slots would be located in appropriately different positions.

I claim:

1. Shingles constructed of flexible fibrous material, having corners at their weathering ends and having in their body portions slots located diagonally to longitudinal axes of the shingles, a pair of such slots on adjacent shingles being adapted to receive the corners of an overlying shingle when bowed and extended in a diagonal direction.

2. Weather proofing material comprising flexible shingles adapted to be applied in rows and in overlapping relation to one an-

- other upon a surface to be covered thereby, each shingle having slots therein, each of said slots being adapted to receive one of a plurality of projections on each of a pair 5 of overlapping shingles, the projections on said overlapping shingles being received in slots in shingles of an adjacent and horizontally spaced row, the spaced horizontal distance between the slots in two rows of 10 shingles being less than that of the width of each shingle; whereby the shingles must be flexed to interlock their projections in said slots.
3. Weatherproofing covering, comprising 15 shingles having approximately rectangular ends providing corners and having slots with closed ends formed through the bodies of the shingles in positions to receive similar corners of shingles lapped in intended relation thereto. 20
4. Weatherproofing material comprising flexible fibrous roofing having outwardly converging slots therein and adapted to be laid to locate the slots in spaced pairs, and flexible fibrous overlapping members having projections engaging said slots, the spaced horizontal distance between each pair of slots being less than the width of each of the overlapping members; whereby the overlapping members must be flexed to insert 25 30 their projections in said slots.

Signed at Chicago, Illinois, this 29th day of December, 1923.

ALBERT C. FISCHER.

CERTIFICATE OF CORRECTION.

Patent No. 1,595,080.

Granted August 10, 1926, to

ALBERT C. FISCHER.

It is hereby certified that the State of Incorporation of the assignee in the above numbered patent was erroneously given as "Illinois", whereas said State should have been given as "Delaware", as shown by the records of assignments in this office; and that the said Letters Patent should be read with this correction therein that the same may conform to the record of the case in the Patent Office.

Signed and sealed this 13th day of March, A. D. 1928.

Seal.

M. J. Moore,
Acting Commissioner of Patents.
